UNITED STATES PATENT OFFICE.

DAVID M. LIGHT, OF SPRINGFIELD, MISSOURI.

STEAM-BOILER FIRE-BOX.

1,162,295.

Specification of Letters Patent. Patented Nov. 30, 1915.

Application filed June 5, 1915. Serial No. 32,268.

To all whom it may concern:

Be it known that I, DAVID M. LIGHT, of Springfield, in the county of Greene and State of Missouri, have invented a certain 5 new and useful Improvement in Steam-Boiler Fire-Boxes, of which improvement the following is a specification.

My invention particularly relates to fire-boxes for steam boilers of the locomotive type, 10 and its object is to provide a firebox of such character which shall be of simple and inexpensive construction, and ready applicability in any of the present standard forms of locomotive boilers, and shall afford the practical 15 advantages, among others, over those of the ordinary construction, of enabling the area of water heating surface to be substantially increased and insuring a more rapid and effective circulation of water over the same; 20 wholly eliminating the large number of side water leg stay bolts ordinarily required; and affording ready access to all of its constituent members for purposes of cleaning, repair, or renewal.

25 The improvement claimed is hereinafter fully set forth.

In the accompanying drawings: Figure 1 is a vertical longitudinal central section through the firebox and the rear portion of 30 the waist of a locomotive boiler, illustrating an embodiment of my invention; Fig. 2, a view, the left hand half of which is a rear elevation of the firebox, and the right hand half, a vertical transverse section, on the 35 line $\alpha\alpha$ of Fig. 1; and Fig. 3, a horizontal section, on the line yy of Fig. 1.

In the practice of my invention, I provide a firebox which is preferably, as shown, of substantially rectangular horizontal section, and which, preliminarily and generally considered, comprises, as essentials, what may be termed a top header, which is designated herein, as an entirety, by the reference symbol, A; a front transverse water leg, 40 designated, as an entirety, by B; a back transverse water leg, designated, as an entirety, by C; and a plurality of water tubes, D, connecting the front and back water legs on each side of the firebox. The structural 45 details of the above recited members of the firebox, and their relation, one to another and to the waist of the boiler, will now be 50 described.

The constituents of the top header, A, are 55 the outside roof sheet or wrapper sheet, 1, and the crown sheet, 2, of the firebox, the

roof sheet being, in the instance exemplified, shown as of the ordinary segmental form, and as connected to the crown sheet by radial stays, 3. The form of the roof sheet 60 and the particular means of staying the crown sheet, are not, however, essentials of my invention, as it is equally applicable in connection with a firebox having a top of the Belpaire flat or Player curved design, 65 and with crown bars or any other preferred form of crown sheet stays.

The sides of the roof sheet, 1, are inwardly curved to a substantially semi-circular section, and connected by seams of rivets to the 70 crown sheet, 2, thereby forming downwardly depending lateral water chambers on the top header, A, and making its transverse section substantially in the form of a crescent, as clearly shown in Fig. 2. Said lateral water chambers are also preferably, as 75 shown in Fig. 1, made of gradually increasing depth from their rear to their front ends, thereby maintaining their bottoms parallel with the subjacent water tubes, D, 80 hereinafter described, and imparting the maximum amount of water heating surface to the header. The lateral water chambers may, if preferred, be formed by the interposition of separate sheets, 1^a, bent to semi-circular transverse section, between the roof sheet and the sides of the crown sheet. The front and back ends of the top header, A, 85 are entirely open, for communication with the waist of the boiler and with the back water leg, C, respectively, and the front end of the roof sheet is connected by rivets to the rear waist sheet, 11, of the boiler.

The back water leg, C, is composed of the back head sheet, 4, and the door sheet, 5, 95 which sheets are connected, by a seam of rivets extending around the fire door opening, 6; by stay bolts, 7, in the ordinary manner; and by seams of rivets, 8, at the sides of the sheets. The only flange which is 100 formed on the door sheet, 5, other than that which projects around the fire door opening, is a flange, 5^a, which is turned forwardly at the top of the sheet and is connected, by a seam of rivets, to the rear end of the crown 105 sheet, 2. The sides of the door sheet are therefore flat or plane, and those of the back head sheet, 4, are turned into reversed curve or S formed flanges, 4^a, the outer faces of which are connected to the flat sides of the 110 door sheet by the seams of rivets, 8. Stiffening plates, 4^d, may, if desired, be interposed

between the back head sheet and door sheet along their lines of riveted connection, and similar plates may also be fitted between the tube sheet and throat sheet.

5 The front water leg, B, is composed of the tube sheet, 9, and the throat sheet, 10, which sheets are connected by stay bolts, 7^a, in the ordinary manner, and by seams of rivets, 8^a, at the sides of the sheets. A forwardly ex-

10 tending flange, 10^b, is turned on the throat sheet, for connection, by rivets, to the adjoining waist sheet, 11, of the boiler, and the tube sheet, 9, is provided, at its top, with a rearwardly extending flange, 9^a,

15 which is connected by rivets to the front end of the crown sheet, 2. The connection of the tube sheet and throat sheet is made in a similar manner to that of the back head sheet and door sheet, as before described, the

20 sides of the tube sheet being without flanges and those of the throat sheet being turned into reversed curve or S formed flanges, 10^a, the outer faces of which are connected to the flat sides of the tube sheet by the seams

25 of rivets, 8^a.

The front and back water legs are connected at each side by, and the side water spaces of the firebox formed by, a plurality of water tubes, D, which are expanded at 30 their ends into the door sheet and tube sheet, and which, for the purpose of promoting the circulation of water, are preferably, as shown, upwardly and rearwardly inclined. The water tubes, D, are disposed

35 at each side of the firebox, in two vertical rows, below the downwardly depending lateral water chambers of the top header, A, the tubes being set at slight distances apart, and relatively staggered in the adjoining

40 rows, in order to present the maximum attainable amount of water heating surface to the calorific action of the gases of combustion which circulate around them. Removable plugs, 4^b, are fitted in the back head

45 sheet, 4, opposite the ends of the water tubes, for the purpose of permitting tube cleaners to be inserted when desired, and these tubes may be provided with smaller plugs, 4^c, to admit of the introduction of water for wash-

50 ing out the tubes. The sides of the firebox, between the front and back water legs, are closed by walls, 12, of fire brick or other suitable refractory material, which are supported on longitudinal bearers, 13, and the

55 side walls, 12, are covered and protected by casings, 12^a, of light plate metal. Air inlets, 12^b, may be formed in the lower rows of bricks of the side walls, to promote the uniform combustion of the fuel on the grate.

60 The bottoms of the front and back water legs are closed by mud rings, 14, which are interposed between and riveted to the sheets of the water legs in the usual manner.

65 Downwardly projecting lugs, 14^a, formed on the mud rings, serve to support the ends of

the bearers, 13, of the side walls, and the grate bars and ash pan, which latter members may be of any suitable and preferred form, and, as they are familiar to those skilled in the art, and do not form part of my present invention, they are not herein shown or described.

I claim as my invention and desire to secure by Letters Patent:

1. The combination, in a steam boiler firebox, of a top header of substantially crescent shaped transverse section, composed of a roof sheet and a connected crown sheet, and having a downwardly depending water chamber on each of its sides; a front transverse water leg composed of a tube sheet and a connected throat sheet; a back transverse water leg composed of a back head sheet and a connected door sheet; and a plurality of water tubes located below each of the lateral water chambers of the top header and connecting the front and back transverse water legs. 75 80

2. The combination, in a steam boiler firebox, of a top header composed of a roof sheet and a crown sheet, connected in substantially the form of a crescent, the side portions of which constitute downwardly depending water chambers in the header, which gradually increase in depth from its rear to its front end; a front transverse water leg composed of a tube sheet and a connected throat sheet; a back transverse water leg composed of a back head sheet and a connected door sheet; and a plurality of water tubes located below, and substantially parallel with, each of the lateral water chambers of the top header, and connecting the front and back transverse water legs. 90 95 100

3. The combination, in a steam boiler firebox, of a top header composed of a roof sheet and a connected crown sheet; a front transverse water leg composed of a tube sheet and a connected throat sheet, the tube sheet having flat sides extending the full width of the throat sheet and being connected through a top flange to the front of the crown sheet, and the throat sheet having lateral flanges connected to the flat sides of the tube sheet; a back transverse water leg composed of a back head sheet and a connected door sheet, the back head sheet being connected through a top flange to the roof sheet and having lateral flanges, and the door sheet having flat sides extending the full width of the back head sheet and being connected through a top flange to the rear of the crown sheet, and through its flat sides to the lateral flanges of the back head sheet; and a plurality of water tubes connecting the front and back transverse water legs, on each side of the firebox. 105 110 115 120 125

4. The combination, in a steam boiler firebox, of a top header composed of a roof sheet and a connected crown sheet; a front

transverse water leg composed of a tube sheet and a connected throat sheet; a back transverse water leg composed of a back head sheet and a connected door sheet; a plurality of water tubes connecting the front and back transverse water legs, on each side of the firebox; mud rings closing the bottoms of the water legs and having down- wardly projecting lugs; walls of refractory material closing the sides of the firebox; and longitudinal bearers supporting said walls and connected to the lugs of the mud rings.
